UNITED STATES PATENT OFFICE.

ANDERS GUSTAF ANDERSON, OF NEW YORK, N. Y.

LOCK.

1,038,512.

Specification of Letters Patent. Patented Sept. 17, 1912.

Application filed November 20, 1911. Serial No. 661,300.

To all whom it may concern:

Be it known that I, ANDERS GUSTAF ANDERSON, a citizen of Sweden, and resident of the borough of Manhattan, in the county of 5 New York and State of New York, have invented certain new and useful Improvements in Locks, of which the following is a specification.

This invention relates to locks and more 10 particularly to that type of lock which can be manipulated at one side of the door only in such manner as to hold the lock against operation.

One of the objects of the invention is the 15 production of an inexpensive durable lock with the fewest possible parts, and capable of being manufactured with the least amount of machine and hand fitting.

Another object is to produce a lock adapt- 20 ed for use in any position, which can be locked from one side of the door without the use of a key or extra latch.

A further object is the production of a 25 lock of this general character wherein the locking part is held against misplacement, either in operative or inoperative position.

The invention consists in the parts, im- 30 provements and combinations hereinafter described and claimed for accomplishing these objects.

In the accompanying drawings, which 35 illustrate the invention and are hereby made a part of this specification, Figure 1 is a partial central plan section of the invention; Fig. 2 is a front view of the lock shown in Fig. 1, parts being omitted; Fig. 3 is a rear view of Fig. 2 with the back wall cut away and some of the parts in a changed position; Fig. 4 is a section on the line 4—4 of 40 Fig. 2, looking in the direction of the arrows; and Fig. 5 is a section on the line 5—5 of Fig. 2 looking in the direction of the arrows.

The lock has a casing consisting of a body 45 10 and a cover plate 11, secured together by two screws 12 and 12^a, 13 is the bolt, preferably beveled at one side at its end. The casing is set into the door 14 in any suitable or usual manner, and handles 15, 15^a are 50 provided at opposite sides of the door. These handles are secured to square stems 16, 16^a as by means of screws 17, and the stems are secured together so as to be capable of independent rotation by means of a

threaded extension 18 on one stem taking 55 into a socket screw thread in the other stem. The engagement between the extension and socket screw threads is loose and the end movement resulting from relative turning of the stems is unimportant. 60

The stems project through openings in the back wall and cover plate of the casing, and hubs 19, 19^a journaled in this wall and plate are secured directly on the stems inside the casing. A single arm lever 20 is 65 formed on the hub 19 and double-arm lever 21 is formed on the hub 19^a.

The bolt 13 has a yoke 22 formed thereon at its rear end. This yoke is shown as a substantially rectangular or oblong frame 70 extending above and below the bolt. The levers 20 and 21 are located within this yoke. The relation of the single-arm lever 20 to the yoke is such that when turned in one direction by its handle, it engages with 75 the forward inner wall of the yoke, so as to constitute a thrust member barring or locking the bolt in thrown or projected position against retraction. But when this lever is turned in the opposite direction by 80 means of its handle, it engages with the back inner wall of the yoke so as to retract the bolt. The yoke is provided centrally of its front inner wall with a projection or stop 23, which prevents the lever 85 being turned past locking or approximately horizontal position. In order that the handle 15, which operates this lever, may be turned in the desired direction, that is, with the nose of the lever 20 below the stop 23, 90 to lock or retract the bolt, irrespective of the position of the lock with reference to the door, the lever 20 is reversible on the stem 16, so that it may operate at either side of the stop 23. This is accomplished by 95 slipping the hub 19 and arm 20 off the square stem, reversing the lever and replacing it. The path of the lever 20 in either direction is indicated by the dash-and-dot line 30. 100

The double arm lever 21 is so related to the yoke that it is incapable of locking the bolt, but one arm or the other will engage with the back wall of the yoke when the handle 15^a is turned in either direction, so as 105 to retract the bolt.

A vertical plate 24 is located at the side of the yoke 22, with its rear edge 25 adja-

cent but partially in rear of the front inner wall of the yoke, in order to prevent the latter from traveling past the edge of the plate. As shown, this edge of the plate 24 is formed so as to afford inclined edges or surfaces intersecting the path of the arm 20 to and from locking position, so that the movement of the arm necessitates the displacement of the plate. The latter is pivot-
10 ed on one screw 12 and has a lug 26 which contacts with the other screw 12^a as a limit stop. A single coil spring 27 is interposed between an offset seat 28 on the bolt and a seat 29 on the plate 24. This spring acts
15 both to project the bolt and to press the plate 24 against the lower stop screw 12^a in the position shown in Figs. 2 and 3.

In operation, the bolt may be locked in thrown position at one side of the door only, 20 by means of the handle 15 and the single arm lever 20. This handle and lever also enable the bolt to be retracted, at the other side of the door, the bolt may be retracted, when it is not locked by the single arm lever 25 20, by means of the handle 15^a and the double arm lever 21. Movement of the handle 15^a in either direction will accomplish this result, but will not lock the bolt. The spring-pressed plate 24 acts as yielding-
30 30 detent, over which the arm 20 must ride in order to reach or leave the locking position shown in Fig. 2. The plate is so formed that it yielding holds the lever 20 either in or out of locking position, as the case may be, so that accidental displacement
35 of the lever is prevented.

Having described my invention what I desire to secure by Letters Patent and claim is:

40 1. In a lock, the combination of a bolt, a spring for throwing the same, handles at opposite sides of the lock having independently rotatable stems, a single arm lever on one of said stems constructed and arranged 45 to directly hold the bolt in locked position when its stem is turned in one direction and also to retract the bolt when its stem is turned in the opposite direction, and a double arm lever on the other stem constructed and arranged to retract the bolt 50 when said stem is turned in either direction, but incapable of locking the bolt.

2. In a lock, the combination of a bolt having a yoke, handles at opposite sides of the lock having independently rotatable stems, an arm on one of said stems located within the yoke and constructed and arranged to engage with the front of the yoke to throw and directly hold the bolt in locked 55 position and with the back of the yoke to retract the bolt, and a double arm lever on the other stem also located within said yoke and adapted to engage with the back of the yoke when its stem is turned in either direction to retract the bolt.

3. In a lock, the combination of a bolt, a handle, an arm carried by the handle constructed and arranged to throw and directly hold the bolt in locked position, a plate pivoted to one side of said bolt and said arm, 70 having the edge thereof bearing against the face of the arm, being positioned so that the latter displaces it in moving to and from locking position, and means pressing said plate against the arm so as to retain it in 75 either position.

4. In a lock, the combination of a sectional casing, screws connecting the sections thereof together, a bolt, a handle, a lever connected with the handle and constructed 80 and arranged to lock the bolt in thrown position, a yielding detent for holding the arm positioned so that the arm rides against and displaces it, said detent being pivoted on one of said screws and engaging with another thereof as a limit stop, and a spring 85 acting on said detent in opposition to the arm.

5. In a lock, the combination of a bolt having a yoke, a handle, a lever connected 90 with the handle and located inside said yoke, said lever being constructed and arranged to engage with the front part of the yoke to lock the bolt in thrown position and with the back part of the yoke to retract the bolt 95 and a spring-pressed plate for yieldingly holding the lever, being pivoted independently of the bolt by the side of said yoke with an edge in position intercepting the path of said lever to and from locking position. 100

6. In a lock, the combination of a bolt, a handle, a lever connected with the handle and constructed and arranged when moved in one direction to lock the bolt in thrown 105 position and when moved in the opposite direction to retract the bolt, a yielding detent for holding said lever, and a spring interposed between said bolt and detent so as to actuate both. 110

7. In a lock, the combination of a bolt, handles at opposite sides of the lock having independently rotatable stems, a single arm lever on one of said stems constructed and arranged to throw and directly hold the bolt 115 in locked position when its stem is turned in one direction, said single arm lever being also adapted to retract the bolt when its stem is turned in the opposite direction, a double arm lever on the other stem constructed and arranged to retract the bolt when its stem is turned in either direction, and means independent of said bolt for retaining the single arm lever in substantially direct alinement with the bolt when the latter is protracted. 120

8. In a lock, the combination of a bolt, a handle having a stem, and a bolt actuating and locking arm mounted on said stem, said bolt having a portion arranged to be en- 130

gaged by said arm to retract the bolt and a portion arranged to be engaged by the arm to lock the bolt in thrown position, said bolt being further provided with a central stop 5 preventing said arm passing locking position, said arm being reversible on said stem so as to operate at either side of said stop.

Signed at the borough of Manhattan in the county of New York and State of New York this 18th day of November A. D. 1911. 10
